(57) **CLAIM**

The ornamental design for a drinking cup, as shown and described.

DESCRIPTION

FIG. 1 is a top and front perspective view of a drinking cup, showing our new design.

FIG. 2 is a top and left side perspective view of the drinking cup of FIG. 1.

FIG. 3 is a top and right side perspective view of the drinking cup of FIG. 1.

FIG. 4 is a top and back side perspective view of the drinking cup of FIG. 1.

FIG. 5 is a bottom and front side perspective view of the drinking cup of FIG. 1.

FIG. 6 is a top plan view of the drinking cup of FIG. 1.

FIG. 7 is a bottom plan view of the drinking cup of FIG. 1.

FIG. 8 is a front elevational view of the drinking cup of FIG. 1.

FIG. 9 is a right side elevational view of the drinking cup of FIG. 1.

FIG. 10 is a left side elevational view of the drinking cup of FIG. 1.

FIG. 11 is a back side elevational view of the drinking cup of FIG. 1; and,

FIG. 12 is a cross-sectional view of our new design for a drinking cup taken along line 12-12 in FIG. 8.

The portions of the drinking cup shown in broken line form no part of the claimed design.

1 Claim, 11 Drawing Sheets
